DISPENSING CONTAINER FOR DRY PRODUCTS

Roland O. Oltman, 5708 N. Euclid, Gladstone, Mo.
64118, and Kenneth R. McHardy, 3509 Blue Ridge
Blvd., Independence, Mo. 64052

Filed Aug. 2, 1967, Ser. No. 8,094

Term of patent 14 years

Int. Cl. D9—07

U.S. Cl. D9—207

FIG. 1

FIG. 2

FIG. 3

FIG. 4

FIG. 5

FIGURE 1 is a front view of a dispensing container for dry products showing our new design;

FIGURE 2 is a side view thereof;

FIGURE 3 is a top view thereof;

FIGURE 4 is a bottom view thereof; and

FIGURE 5 is an enlarged cross-sectional view of the top portion taken on the line 5—5 of FIG. 3.

The dominant features of our design reside in the portions shown in full lines.

We claim:

The ornamental design for a dispensing container for dry products, substantially as shown and described.
